(57) **CLAIM**

The ornamental design for an elevated visor for a cap and other headworn articles, as shown and described.

DESCRIPTION

FIG. 1 is a perspective view of a low brim embodiment of an elevated visor for a cap and other headworn articles showing my design as seen from the lower left;

FIG. 2 is a perspective view of my design shown in FIG. 1 as seen from the front left;

FIG. 3 is a front elevation view of my design shown in FIG. 1;

FIG. 4 is a rear elevation view of my design shown in FIG. 1;

FIG. 5 is a left side elevational view of my design shown in FIG. 1;

FIG. 6 is a top plan view of my design shown in FIG. 1;

FIG. 7 is a bottom plan view of my design shown in FIG. 1; and,

FIG. 8 is a perspective view of a second embodiment of an elevated visor for a cap and other headworn articles showing my new design, the only difference being the high brim, the opposite perspective view is a mirror image.
